(57) **CLAIM**

The ornamental design for a safe, as shown and described.

DESCRIPTION

FIG. 1 is a perspective view of a safe according to an embodiment of the present design with a door, door hinges, a combination entry keypad, and a handle assembly shown in broken lines.

FIG. 2 is a front elevation view of the safe of FIG. 1 with the door, door hinges, combination entry keypad, and handle assembly shown in broken lines.

FIG. 3 is a rear elevation view of the safe of FIG. 1.

FIG. 4 is a right side elevation view of the safe of FIG. 1 with the door hinges, handle assembly, and combination entry keypad shown in broken lines.

FIG. 5 is a left side elevation view of the safe of FIG. 1 with the door hinges, handle assembly, and the combination entry keypad shown in broken lines.

FIG. 6 is a top plan view of the safe of FIG. 1 with the handle assembly, door hinges, and the combination entry keypad shown in broken lines; and,

FIG. 7 is a bottom plan view of the safe of FIG. 1 with the handle assembly, door hinges, and the combination entry keypad shown in broken lines.

The broken lines shown in FIGS. 1 through 7 illustrate portions of the safe that form no part of the claimed design.
